DESIGN FOR A TOY AUTOMOBILE

Elmer R. Roach, Mount Vernon, Ohio

Application April 2, 1945, Serial No. 118,811

Term of patent 14 years

(Cl. D34—15)

To all whom it may concern:

Be it known that I, Elmer R. Roach, a citizen of the United States, residing at Mount Vernon, in the county of Knox and State of Ohio, have invented a new, original, and ornamental Design for Toy Automobile, of which the following is a specification, reference being had to the accompanying drawing, forming a part thereof,

and wherein Fig. 1 is a perspective view and Fig. 2 a plan view of a toy automobile showing my new design.

I claim:

The ornamental design for a toy automobile, as shown.

ELMER R. ROACH.
